UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,347,746.

Specification of Letters Patent. Patented July 27, 1920.

Original application filed November 30, 1917, Serial No. 204,534. Divided and this application filed March 29, 1919. Serial No. 286,221.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing, being a division of 10 original application filed November 30, 1917, Serial No. 204,534.

My invention relates to typographical machines, such as linotype machines of the general organization represented in Letters 15 Patent of the United States to O. Mergenthaler, No. 436,532, wherein circulating matrices are released from a magazine in the order in which their characters are to appear in print and then assembled in line, 20 the composed line transferred to the face of a mold, the mold filled with molten metal to form a slug or linotype against the matrices which produce the type characters thereon, and the matrices thereafter re- 25 turned through a distributing mechanism to the magazine from which they started.

My invention, generally speaking, is intended to adapt these machines for handling matrices with characters of greatly increased size or point, such as are used in 30 advertising matter or display work. The ordinary linotype machine is not entirely adapted to this class of work for a variety of reasons, and principally because the machine elements are not capable of handling 35 matrices of a size that would be required to carry the enlarged characters. Thus, heretofore, the magazines have been limited in width to that of the keyboard, due to 40 the form of connections between these parts, etc., and hence it is impossible to store all the matrices of a complete font such as I propose to use in any one of such magazines because of its reduced size. The present 45 machine is organized along a different principle and contemplates the use of magazines of such size that each may contain a complete font of the required matrices, involving a radical departure in the form and 50 arrangement of the parts as will appear in the detailed description to follow.

In the accompanying drawings, for the sake of simplicity, I have shown my improvements in connection with a single

magazine only, but it should be understood 55 that they may be embodied in a machine employing a movable series of magazines, such as illustrated in my pending application Serial No. 204,534, filed November 30, 1917, of which the present application is a 60 division, or in any other class of machine to which the invention is applicable. In addition, I have shown my invention only in preferred form and by way of example, and obviously many changes and variations 65 may be made therein and in its mode of application and still be comprised within its spirit. Generally speaking, I desire it to be understood that I do not limit myself to any specific form or embodiment, except in so far as such limitations are specified in the claims.

Referring to the drawings:

Figure 1 is a side elevation (partly in section) of a portion of a linotype machine 75 having my invention applied thereto;

Fig. 2 is a front elevation of the machine on an enlarged scale;

Fig. 3 is a diagram illustrating the connections between the keyboard and the magazine;

Fig. 4 is a front view partly in section of a portion of the keyboard and its operating connections;

Fig. 5 is a side elevation of the keyboard 85 broken away at the rear to expose its connections with the escapement operating reeds which are shown in vertical section; and

Figs. 6 and 6^a are top plan and front 90 views, respectively, of a portion of the keyboard connections detached.

The matrices X are stored in the magazine A, which is sustained by the supplemental frame g in registration at its lower 95 end with the fixed throat C communicating with the usual front plate or raceway C¹, and at its upper end with the magazine entrance F² leading from the distributor F.

The matrices are released from the magazine by a single series of escapements C² located in the throat C and actuated by reeds C³, and each comprising, as usual, (Fig. 1) a pivoted lever and two pawls which are projected thereby alternately into 105 the throat in effecting the release of the matrix. The arrangement and operation of the escapements are the same as shown and

described in my previous Letters Patent No. 1,115,211, and therefore require no further description here. It may be stated, however, that the action of the escapements 5 is such that they hold the lowermost matrices in the magazine and after their actuation leave the throat C entirely clear of matrices, so that the magazine is free to be moved or removed at any time without pre- 10 paratory operations. The removal of the magazine is effected in the well known manner. As shown, the frame g is provided with the usual cam pieces g⁴, coöperating with rollers g⁵ on the bracket plates g³, and 15 which by being drawn forwardly rock the supporting frame g upwardly about the bar G⁴ as a pivot to locate the magazine above the assembling devices.

The parts so far described, except as here- 20 inafter pointed out, may be of any well known or approved construction or, as illustrated in the parent application above referred to. As before stated, the present invention is directed to a new relation between 25 and in the form of the magazine and the assembling devices as will now be described.

By referring to Fig. 2, it will be seen that the magazines are much wider than the keyboard which, in prior machines, has been of 30 the same width, and in addition, they are made much shorter than those ordinarily employed (see Fig. 1). By thus shortening the magazines, the weight of the parts is materially reduced and the machine rendered 35 more compact than if the magazines were of full normal length. I have found that, in respect to most of the characters, there is no danger of the supply of matrices becoming exhausted because of the short magazines, 40 and as to those more frequently used, I have allotted two magazine channels to each, providing mechanism whereby the matrices may be drawn alternately therefrom. I also propose to store the matrices in the magazine 45 in the regular order and to arrange the finger keys in the keyboard in the same order, as customary. Due to the increased width of the magazine as compared with that of the keyboard, it is obvious that the usual con- 50 nections between these parts is unsuitable for the present arrangement, as it is well known that ordinarily each finger key co- operates with its corresponding matrix column through a train of connections lying in 55 a vertical plane which passes substantially through the key and the matrix column. In accordance with my invention, I have provided a system of connections between the finger keys and their corresponding matrix columns such that the keys may stand in different vertical planes from their corresponding channels, although as to some of the keys this relation has been maintained.

The general arrangement of the parts is 65 represented diagrammatically in Fig. 3,

which shows a part of the magazine with its escapements and the connections therefrom to the finger keys of the keyboard, it being noted that the group of escapement actuating reeds C² for the first vertical tier of finger 70 keys (e to n) are disposed entirely to one side of the keys, the same being true as to the second tier of keys (s to u); while as to the third and fourth tiers (c to j) the keys lie substantially in the same planes as their es- 75 capement reeds C³, being connected thereto in the usual manner. All the other tiers of finger keys are connected to their respective groups of escapement reeds by offset connections, the distance between each tier of keys 80 and the corresponding group being greater and greater as the last tier is approached.

Referring now in detail to the construction of the parts, the magazine is provided with as many escapements C² and actuating 85 reeds C³ as there are matrix columns in the magazine. The escapement reeds C² are operated by the yokes C⁴ arranged in two different banks and provided with cams or eccentrics C⁵ adapted under the influence of 90 the trip dogs or triggers C⁶ to coöperate with the underlying power-driven rolls C⁷ in the well known way. The dogs C⁶ are connected as usual to the upper ends of vertical slides C⁸, which are suitably supported 95 in the framework and are adapted to be raised by the manipulation of the finger keys C⁹ of the keyboard C¹⁰. The two tiers of finger keys bearing the letters c to j are connected directly to the corresponding 100 slides C⁸, so that such keys and their connections stand in the same vertical planes as their respective escapement reeds, as heretofore. The keys of the remaining tiers, however, are attached at their rear ends to short 105 idle slides C¹¹ which are connected to the corresponding cam releasing slides C⁸ located at a different point in the width of the keyboard, the keys thus being offset from the matrix columns which they control. The 110 connection between the slides C¹¹ and C⁸ in the present instance is in the form of U-shaped straps or bails C¹² whose parallel arms engage in notches or recesses in the 115 rear edges of the slides. By means of this connection, therefore, a finger key occupying its usual place in the keyboard is capable of controlling the operation of its cam yoke located in the plane of the escapement reed or matrix column which is situated remote 120 from the key. Preferably, and as shown, these bails are arranged in groups corresponding to the arrangement of the escapement actuating reeds, there being six in each group, one overlying the other and mounted 125 to rock upon long pivot rods C¹³ extending from one side of the keyboard to the other. It will be noted that the bails vary in length in the different groups corresponding to the varying distances between the tiers of finger 130

keys and the groups of escapement reeds controlled thereby, as plainly indicated in Figs. 6 and 6*. This group arrangement of the bails and escapement reeds is advantageous for a variety of reasons, not only reducing the cost of manufacture but greatly simplifying the construction.

The six pivot rods C^{13} are common to all the groups of connecting bails, each rod giving support to the corresponding bails of all the groups arranged at the same level. These pivot rods with the bails thereon are mounted in a box-like structure comprising the longitudinal parallel plates P secured together at their opposite ends by the cross plates P^1 . The pivot rods C^{13} are fitted into the side members P^1 , while the arms of the bails C^{12} project forwardly throughout slotted openings in the front plate P to make engagement with the key actuated slides, the openings P^2 being of such character as to permit a limited rocking of the bails such as is required in communicating the movements of the slides C^{11} to the cam releasing slides C^8 . As thus arranged the box-like structure P , P^1 , with the contained bails and pivot rods, may be readily applied to or removed from the machine as a unit, the loose engagement between the bails and the actuating slides C^{11} and C^8 being made and broken as the unit is applied or removed. When in place the unit is fixed to the machine by means of screws P^3 passing through extensions in the front plate P of the supporting structure. If desired, pointed pins P^4 may be employed to aid in locating the parts in their proper position (Fig. 6). In this construction, it may be noted that the pivot rods C^{13} are capable of being withdrawn endwise to disassemble the parts, the rods being held in place by a locking strip P^5 engaging in circumferential grooves in the exposed ends of the rods.

If desired, the bails C^{12} could be applied at a different point in the connections between the keyboard and the magazine. Thus, instead of being arranged between the finger keys C^9 and the power-operated cam yokes C^4 , as shown, they could be arranged between the cam yokes and the escapement reeds C^8 , in which event the yokes would be operated directly by and located in the planes of the corresponding finger keys (as in the case of the two tiers c to j) and the idle slides C^{11} would be arranged above and in the planes of the yokes and their reciprocations transmitted through the bails to the escapement reeds.

As before indicated, I propose to store the more frequently used matrices in duplicate channels of the magazines, such as those bearing the characters e, t, a, o, i and n (represented in the first tier of finger keys), and em, en and th (represented in the sixth, seventh and eighth tiers of keys, respectively).

The magazine is therefore provided with so many additional channels and a corresponding number of escapements C^2 and actuating reeds C^3 , it being noted by referring to the diagram of Fig. 3 that six reeds have been added to the group represented by the first tier of finger keys, and one added to each of the groups represented by the sixth, seventh and eighth tiers of keys. The escapement reeds associated with all the duplicate channels are shorter than the remaining reeds, and are supported in the framework some distance above the operating cam yokes C^4 , as clearly shown in Fig. 4. Interposed between these escapement reeds and the cam yokes are short rods or sections D supported with their lower ends in permanent engaging relation to the cam yokes C^4 and which are arranged to be moved laterally at their upper ends to be connected alternately with first one and then the other of the two sets of overlying escapement reeds. Thus, for the characters e, t, a, o, i and n, there are six intermediate rods D to cooperate with the twelve escapement reeds serving the magazine channels wherein the matrices bearing these characters are stored, so that when the rods are shifted to the left they will operate every other escapement reed of the group, and when to the right the intermediate escapement reeds, thus causing the matrices to be delivered alternately from their respective duplicate channels. The same arrangement is true as to the characters em, en and th, except that for each there is but one adjustable rod D employed to make the alternate connection of the corresponding finger key with the two associated escapement reeds.

The lateral adjustment of the rods D as above described is effected by means of a longitudinal shiftable bar D^1 formed with laterally projecting guide or comb plates D^2 wherein the upper ends of the sections engage. This bar is supported in the machine frame by a pin and slot connection D^3 and a sliding plunger D^4 , which latter is loosely attached to the upper end of an operating lever D^5 pivoted centrally as at D^6 to the frame. A spring D^7 acting on the lever above its pivot tends constantly to shift the bar D^1 to the left and to maintain the lower end of the lever in engagement with a rotatable face cam D^8 having alternate risers and depressions D^9 and D^{10} . See Rogers U. S. Patent No. 1,188,730. As a result of this construction, when the lower end of the lever D^5 engages in one of the depressions D^{10} of the cam, the bar D^1 is shifted to and maintained in its position to the left, presenting the rods D in operative relation to the leftmost escapement reeds C^3 . When, however, the lower end of the lever engages one of the risers D^9 of the cam, the bar is shifted to and maintained in

its position to the right, causing the rods D to be presented in operative relation to the rightmost escapement reeds. In other words, the rotation of the cam D⁸ acts through the connections described to shift the rods D alternately to the right and left to connect different escapement reeds with the cam yokes and their controlling finger keys.

- 10 The rotation of the cam D⁸ is effected by means of an attached ratchet wheel D¹¹ having as many teeth as there are risers and depressions on the cam and adapted to be rotated by a reciprocating pawl D¹². The 15 pawl D¹² is carried by a pivoted bell crank lever D¹³ connected by a link D¹⁴ to the lever D¹⁵, which latter forms a part of the operating connections for the usual assembling elevator D¹⁶ wherein the matrices are 20 composed in line (Fig. 2). For a detailed showing and description of these cam operating parts, reference may be had to the Rogers Patent No. 1,188,730. The effect of the arrangement in the present instance is 25 that when the assembler is elevated for the transfer of the composed line, the cam D⁸ will be rotated the distance of one tooth to bring either a riser or depression thereof into action, so that by the repeated operations of the assembler a change will be 30 effected between the duplicate magazine channels.

The distributor F is supported in the so-called distributor bracket Z, which constitutes the upper portion of the main frame. Ordinarily, this bracket is of U-shape form with its two arms substantially straight and parallel and pointing upward for the attachment thereto of the distributor parts. 40 In the present instance, the two arms are extended forwardly from the connecting or base portion of the bracket, as shown in Fig. 1, so as to locate the distributor nearer to the front of the machine and at a lower 45 level than customary. This new location of the distributor thus adapts it to coöperate with the improved magazine, which as previously stated is of less than normal length.

The improved wide and short magazine herein shown and described presents many advantages: It not only reduces the weight of the parts because of its shorter length and the fewer matrices employed and thus permits the interchange of magazines with 55 the same ease and facility as ordinary magazines, but it enables those parts to be manufactured and sold at comparatively small cost, thus permitting a large number of magazines with different fonts to be kept on 60 hand for ready interchange in the production of the varied forms of printed matter desired. In addition, the construction of the machine itself is greatly simplified and rendered more compact than would be possible in the use of magazines of ordinary or

full length. Thus, the width of the magazine at its upper end is materially reduced, permitting and effecting a corresponding reduction in the width of the magazine entrance and in the length of the distributor, 70 which latter in their new relations are not much greater in extent than the assembling devices themselves. These and various other advantages will be apparent to those versed in the art.

75 As previously stated, I have shown my improvements merely in preferred form and by way of example and as applied to the particular kind of machine described, but it will be obvious that many modifications and alterations will readily suggest themselves to those skilled in the art without departing from the scope of the invention.

80 Having thus described my invention, its 85 construction and mode of operation, what I claim and desire to secure by Letters Patent of the United States is as follows:

1. In a typographical machine, the combination of a keyboard comprising finger 90 keys, a magazine of materially greater width at its discharge end than that of the keyboard, matrix releasing escapements associated with the magazine, actuating reeds connected to the escapements and some removed laterally from their corresponding finger keys, and offset connections between the latter keys and the remote escapement actuating reeds. 95

2. In a typographical machine, the combination of a keyboard comprising finger keys, a magazine of materially greater width at its discharge end than that of the keyboard, matrix releasing escapements associated with the magazine, actuating reeds connected to the escapements and some removed laterally from their corresponding finger keys, and intermediate bails connected at one end to the latter finger keys and at the opposite end to the remote escapement 100 actuating reeds. 105

3. In a typographical machine, the combination of a keyboard comprising finger keys, a magazine of materially greater width at its discharge end than that of the keyboard, matrix releasing escapements associated with the magazine, actuating reeds connected to the escapements and some removed laterally from their corresponding finger keys, idle slides connected to and arranged in the planes of the latter finger keys, and laterally extending bails connected at one end to said slides and at the opposite end to the escapement actuating reeds. 110 115 120

4. A structure as specified in claim 1, 125 characterized by the fact that the offset connections therein referred to include power-driven devices or cam yokes for operating the escapement reeds under the influence of the finger keys. 130

5. A structure as specified in claim 2, characterized by the fact that the connections between the bails therein referred to and the escapement reeds include power-driven devices or cam yokes which operate the reeds and which are controlled from the distant finger keys.

6. A structure as specified in claim 1, characterized by the fact that the offset connections therein referred to include a plurality of power-driven devices or cam yokes, one for each finger key, controlling slides connected to said cam yokes, idle slides connected to the finger keys, and intermediate bails for communicating the motion of the idle slides to the controlling slides.

7. A structure as specified in claim 2, characterized by the fact that the escapement actuating reeds and their connecting bails are arranged in groups, the bails of each group being of the same length and disposed at different levels to make connections with the respective parts.

8. A structure as specified in claim 7, characterized by the fact that the bails of all the groups are supported upon a series of pivot rods, each of which is common to the corresponding bails of the several groups.

9. A structure as specified in claim 2, characterized by the fact that the connecting bails are mounted in a supporting structure which is detachably connected to the framework so as to be applied to or removed from the machine as a unit.

10. In a typographical machine, the combination of a group of finger keys, a corresponding group of cam yokes, one only for each finger key, controlling slides connected

to the cam yokes, idle slides connected to the finger keys, and intermediate U-shaped bails connecting the two sets of slides and mounted to rock about transverse axes to communicate motion from one to the other.

11. In a typographical machine, the combination of a channeled matrix magazine having single channels for most of the matrices and duplicate channels for those more frequently used, a bank of escapements controlling the release of the matrices from the magazine, and a keyboard mechanism operatively connected to the escapements and including indirect connections between some of the finger keys and their corresponding escapements, the said indirect connections being extended to the escapements for both the single magazine channels and the duplicate magazine channels.

12. In a typographical machine, the combination of two matrix releasing escapements, two escapement actuating reeds, a single finger key removed laterally from both of said reeds, and laterally offset devices between the finger key and the two escapement actuating reeds, said connections

being adjustable to establish an operative connection between the finger key and either one of said reeds.

13. In a typographical machine, the combination of a keyboard having its finger keys arranged in vertical tiers, a series of escapement actuating reeds arranged in groups, one for each tier of keys, some of the groups having duplicate reeds arranged side by side therein, and automatic mechanism for connecting the appropriate finger keys of the corresponding tiers alternately to the adjacent duplicate reeds of the respective groups.

14. In a typographical machine, the combination of a plurality of pairs of escapement actuating reeds, the reeds of each pair being arranged side by side, a plurality of key-controlled operating rods, one only for each pair of reeds, and automatic mechanism for simultaneously positioning the operating rods alternately in engaging relation to the reeds of their respective pairs.

15. In a keyboard mechanism for typographical machines, the combination of a group of finger keys, a laterally removed group of power-driven cam-yokes, one only for each finger key, controlling slides connected to and arranged in the planes of the cam-yokes, idle slides connected to and arranged in the planes of the finger keys, and intermediate rocking bails connecting the two sets of slides to communicate motion from one to the other, with a common supporting frame wherein the bails are mounted, the said frame being detachably connected to the machine frame so that all the bails may be applied to or removed from the machine as a unit.

16. In a keyboard mechanism for typographical machines, the combination of a group of finger keys, a laterally removed group of power-driven cam-yokes, one only for each finger key, controlling slides connected to and arranged in the planes of the cam-yokes, idle slides connected to and arranged in the planes of the finger keys, and intermediate rocking bails connecting the two sets of slides to communicate motion from one to the other, the said bails being of the same length and disposed at different levels to make connection with the two sets of slides.

17. In a keyboard mechanism for typographical machines, the combination of a series of finger keys, a series of power-driven cam-yokes, one only for each finger key, controlling slides connected to and arranged in the planes of the respective cam-yokes, idle slides connected to and arranged in the planes of the respective finger keys, and intermediate rocking bails connecting the two series of slides to communicate motion from one to the other, the said bails being arranged in groups and the bails of each

group being of the same length and disposed at different levels to make connection with the respective parts.

18. In a keyboard mechanism for typographical machines, the combination of a series of finger keys, a series of power-driven cam-yokes, one only for each finger key, controlling slides connected to and arranged in the planes of the respective cam-yokes, idle slides and intermediate rocking bails connecting the two series of slides to communicate motion from one to the other, the said bails being arranged in groups and

the bails of each group being of the same length and disposed at different levels to 15 make connection with the respective parts, with a common supporting frame detachably connected to the machine frame and provided with a series of pivot rods upon which the bails of the several groups are 20 mounted, each of said pivot rods being common to the corresponding bails of the several groups.

In testimony whereof, I have affixed my signature hereto.

DAVID S. KENNEDY.
